OVERBED TABLE

George R. Chervenka, 6245 Kinsey Place, St. Louis, Mo.

Filed Aug. 8, 1960, Ser. No. 61,662

Term of patent 14 years

(Cl. D33—14)

FIG. 1

FIG. 2

Fig. 1 is a side elevational view of an overbed table embodying my new design;

Fig. 2 is a top plan view thereof;

Fig. 3 is a front elevational view thereof;

Fig. 4 is a rear elevational view thereof; and

Fig. 5 is a perspective view thereof showing the basin in outwardly swung position.

I claim:

The ornamental design for an overbed table, substantially as shown.
